220,337

PORTABLE ELECTRICAL GROUND FAULT INTERRUPTER

Ernest R. Carlson, Fairfield, Conn., assignor to Harvey
Hubbell Incorporated, Bridgeport, Conn.

Filed Mar. 11, 1970, Ser. No. 21,850

Term of patent 14 years

Int. Cl. D13—03

U.S. Cl. D26—13

Fig. 2.

Fig. 3.

Fig. 5.

Fig. 4.

Fig. 6.

FIG. 1 is a front perspective view of a portable electrical ground fault interrupter or similar article embodying my new design;

FIG. 2 is a top plan view thereof;

FIG. 3 is an elevational view thereof showing the other side;

FIG. 4 is a bottom plan view thereof;

FIG. 5 is a front elevational view thereof, and

FIG. 6 is a rear elevational view thereof.

The broken line showing of the conventional electrical receptacle portions in FIGS. 1, 2 and 5 is for illustrative purposes only.

I claim:

The ornamental design for a portable electrical ground fault interrupter, substantially as shown and described.
